Primary Examiner — Kevin K. Rudzinski*Assistant Examiner* — Clare Ann Gannon(74) *Attorney, Agent, or Firm* — Kintner IP, LLC; Mary Frances Ludwig(57) **CLAIM**

The ornamental design for a garment fastener, as shown and described.

DESCRIPTION

FIG. 1 is a perspective view of a garment fastener showing our new design;

FIG. 2 is a front elevation view thereof;

FIG. 3 is a top plan view thereof;

FIG. 4 is a bottom plan view thereof; and,

FIG. 5 is a rear elevation view thereof.

Elements shown in broken lines depict portions of the garment fastener that form no part of the claimed design.
